UNITED STATES PATENT OFFICE

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE

THREAD TRIMMER FOR SEWING MACHINES

Application filed December 15, 1925, Serial No. 75,518. Renewed October 16, 1929.

This invention relates to thread trimmers for sewing machines of that type which are power-actuated and are set in operation for trimming the thread by the action of the 5 stop motion in bring the stitch-forming mechanism to rest.

One of the objects of my present invention is to provide a novel thread trimmer which is arranged so that when the stop motion 10 brings the stitch-forming mechanism to rest at the end of the seam the thread trimmer is automatically coupled to a constantly-moving part which gives the thread trimmer its thread-trimming movement, said thread 15 trimmer being then automatically disconnected from the constantly-moving part after the trimming operation.

The thread trimmer herein shown has a thread holder associated therewith which 20 holds the cut end of the thread leading to the source of supply and maintains such hold on the thread until the stitching on the next seam has begun. The thread cutter is of the 25 type which is arranged not only to trim the thread at the end of each sewing operation but also to trim the held end of the thread after the stitching has begun on the next succeeding sewing operation, the cutter, therefore, cutting the thread twice for each sewing 30 operation, once at the beginning and again at the end.

A further object of the invention is to provide a novel thread trimmer which is actuated by a constantly-rotating member to trim the 35 thread at the end of the sewing operation and is actuated by the means for operating the stitch-forming mechanism to trim the thread at the beginning of the sewing operation.

Other objects of the invention are to improve thread cutters in various respects all 40 as will be more fully hereinafter set forth.

In order to give an understanding of the 45 invention I have illustrated in the drawings a selected embodiment thereof which will now be described after which the novel features will be pointed out in the appended claims.

Fig. 1 is a side view of a sewing machine 50 embodying my invention;

Fig. 2 is an enlarged section on the line 2—2, Fig. 1 looking toward the right;

Fig. 3 is a section on the line 3—3, Fig. 2;

Fig. 4 is a view illustrating the means for operating the thread cutter at the beginning 55 of the sewing operation;

Fig. 5 is an enlarged section on the line 5—5, Fig. 1;

Figs. 6, 7 and 8 are side views of the thread 60 cutter and holder showing the parts in different positions;

Figs. 9, 10 and 11 are plan views of the 65 thread cutter and holder showing the parts in different positions;

Fig. 11^a is a fragmentary perspective view 70 showing the thread holder;

Fig. 12 is a vertical sectional view on substantially the line 12—12, Fig. 1, some of the 75 parts being omitted;

Fig. 13 is a view on the line 13—13, Fig. 70 12 looking upwardly;

Fig. 14 is a detail of the latch 95.

The thread cutter mechanism embodying 80 my invention may be applied to various types of sewing machines which are constructed 75 to perform a predetermined sewing operation and then automatically come to rest. As illustrating some sewing machines of this type I would refer to buttonhole sewing machines and so-called "tackers" which are designed 85 to sew reinforcing stitches such as the barring stitches across the end of the buttonhole or reinforcing stitches or "tacks" at the corners of pockets and in various other locations in garments.

The sewing machine herein illustrated is 90 of the "tacker" type, although as stated above, the invention is equally applicable to buttonhole sewing machines and other sewing machines that perform a predetermined sewing 95 operation and then come to rest.

Referring to Fig. 1, 1 indicates generally 100 the main frame of a sewing machine which is provided with the usual overhanging arm 2 in which reciprocates vertically the needle bar 3 carrying the upper needle 4 of the stitch-forming mechanism. The main frame of the sewing machine herein illustrated is also provided with the portion 5 on which the work *w* is supported, this work being held 105

during the sewing operation by being clamped between an under work clamp 6 and an upper work clamp 7. The complete stitch-forming mechanism comprises not only the needle 4 operating from above the work but also suitable mechanism arranged beneath the work and co-operating with the needle 4 to concatenate the stitches.

The stitch-forming mechanism is operated from a power shaft 8 which in turn is driven from a driving pulley 9. This power shaft 8 is geared by gearing 90 to a horizontal shaft 91 extending longitudinally of the arm 2 and by which the needle bar is reciprocated. The shaft 91 in turn is geared by gearing 92 to a vertical cam shaft 93 which carries the cams that control the feeding of the work and the movement of the work clamps for producing the underlying and overlying stitches of a tack or reinforcing seam and other operations.

Inasmuch as the present invention is not concerned with the operative mechanism carried by the shaft 93 I have not deemed it necessary to illustrate it herein but would refer to my co-pending application Serial No. 726,535 as showing more fully such mechanism.

The driving pulley 9 is loosely mounted on the power shaft 8 but is adapted to be clutched thereto by means of any suitable clutch which is actuated by the cone-shaped actuator 10 that is slidably mounted on the shaft. Movement of the clutch actuator 10 toward the left Fig. 2 will throw the clutch into engagement thus clutching the driving pulley 9 to the shaft 8 and movement of the clutch actuator into the position shown in Fig. 2 will release the clutch.

The clutch actuator 10 is given its reciprocating motion on the shaft through the medium of a forked arm 11, the fork of which engages the groove 12 in the clutch actuator and which extends laterally from the collar 13 fast on a clutch-controlling rod 14 that is slidably mounted in the frame and that is acted on by a suitable spring 15 that tends normally to hold it in the position shown in Fig. 2, in which position the clutch is disengaged and the driving pulley 9 is loose on the shaft. When the clutch-controlling member 14 is moved to the left, thereby compressing the spring 15, such movement will, through the arm 11, shift the clutch actuator 10 to the left and thereby throw the clutch into engagement. This movement of the clutch-controlling member 14 is secured by an elbow lever 16 pivoted at 17 and one arm of which is connected by a link 18 to a treadle. This type of clutch, which forms no part of the present invention, is similar to that illustrated in my Patents No. 1,326,668, December 30, 1919 and No. 1,466,402, August 28, 1923.

Associated with the clutch is a stop motion

device for bringing the shaft 8 and stitch-forming mechanism to rest at the end of each sewing operation. This stop mechanism comprises a stop cam 19 fast on the shaft 8 and a co-operating stop dog 20 which is carried in a block or head 21 that is fast on the controlling rod 14. Said stop dog 20 is yieldingly mounted in the block 21 by reason of its being backed by a spring 22.

When the controlling member 14 is moved to the left by the depression of the treadle or otherwise thereby to throw the clutch into engagement this movement will carry the stop dog 20 longitudinally of the shaft 8 and to one side of the path of movement of the stop cam so that the cam is free to rotate while the clutch is in engagement. The controlling rod or member 14 is retained in this position during the sewing operation by means of a latch 94 which is adapted to engage automatically a shoulder 95 on the controlling member when the latter is moved into a position to clutch the driving pulley 9 to the shaft 8 as seen in Fig. 14. This type of latch for holding the clutch in engagement is similar to that more fully illustrated in my co-pending application Serial No. 726,535, filed July 17, 1924.

At the end of the sewing operation the latch is released from the shoulder 95 by means of a cam projection 96 and when the latch is thus released the spring 15, which was compressed by the clutch-engaging movement of the controlling member 14 returns said controlling member to the position shown in Fig. 2 thereby disengaging the clutch and at the same time bringing the dog 20 into the path of movement of the stop cam 19. When this occurs the cam 19 will engage the end of the dog 20 and the latter will thus bring the shaft 8 to rest, the spring 22 permitting the dog to have a yielding movement so that the stitch-forming mechanism will be brought to rest with a cushioned movement.

The driving and stopping mechanism herein illustrated, therefore, which of itself does not constitute part of my present invention, is one in which the driving member (the pulley 9) is a constantly-rotating member which is operatively connected to the stitch-forming mechanism by means of a clutch.

According to my present invention the actuation of the thread cutter for trimming the thread at the end of the seam is secured from the constantly-rotating member 9 and said thread cutter is set in operation by the action of the stop motion in bringing the stitch-forming mechanism to rest. For this purpose I have provided an operating cam for actuating the thread cutter, which cam is normally idle, and have provided means for automatically clutching the cam to the constantly-rotating member when the stop motion operates to stop the stitch-forming

mechanism whereby the cam will perform its operation of actuating the cutter, and have also provided means for unclutching the cam from the constantly-rotating driving member automatically when the cutter has performed its function.

The thread cutter herein shown is arranged to cut the upper thread *t* which is controlled by the needle 4 and the cutter has associated therewith a thread holder.

In the operation of the device when a sewing operation has been completed the holder will first seize and grip the needle thread and then the cutter will be actuated to cut the thread between the thread holder and the work, the thread holder thus retaining its hold on the end of the thread which extends to the needle. After the next sewing operation has begun the cutter is again actuated to cut the held end of the thread.

The thread holder is in the form of a finger 24 which is fast on the lower end of a rock shaft 25 which is journalled in a head 26 carried on the end of one of the arms 27 and to which the sections of the upper work clamp 7 are secured, these arms 27 being pivoted at 28 to an upstanding portion 29 of a work clamp supporting member, all as shown in my co-pending application Serial No. 73,705, filed December 7, 1925.

This rock shaft 25 is acted on by a spring 30 which normally holds it and the finger 24 in the position shown in Fig. 9, in which position said finger is located at one side of the path of movement of the needle 4, the latter passing through the sewing opening 31 at each penetrating thrust. The thread-gripping finger 24 is convexly-curved on one side and concavely-curved on the other, as clearly seen in Figs. 9 to 11.

At the end of the sewing operation and when the stitch-forming mechanism has been brought to rest with the needle raised the rock shaft 25 is turned to swing the thread-gripping finger 24 to the opposite side of the path of movement of the needle into the position shown in Fig. 10, and dotted line Fig. 11^a, during which movement the convexly-curved side of the finger wipes by the length 50 of thread extending from the needle to the work so that the thread is located on the concavely-curved side of said finger. The thread-gripping finger then swings back to its initial position shown in Figs. 11 and 11^a and during this movement it engages the thread and pulls its laterally over a clamping plate 32 which is secured to the head 26 and is situated directly beneath the thread-holding finger 24. The thread *t* is thus clamped between the clamping plate 32 and the thread-gripping finger 24.

After the thread has been clamped it is cut between the holding means and the work by a thread cutter in the form of a cutting blade 33 that is provided with a cutting edge 34. This

thread cutter is slidably mounted on the head 26 and operates directly beneath the clamping plate 32. Normally the thread cutter 33 is in its retracted position shown in Fig. 9 in which position the cutting edge 34 is situated back of the path of movement of the needle.

As soon as the thread-holding finger 24 has operated to clamp the thread between itself and the clamping plate 32 the thread cutter 33 is moved forwardly thus bringing the cutting edge 34 against the thread between the holding means and the work thereby cutting the thread close to the work. The cut end leading to the needle will be retained by the thread holder until after the next sewing operation has been started.

The movements of the thread-holding finger 24 and the thread cutter 33 which are necessary for holding the thread and cutting it are secured by means of an operating cam which is operatively connected automatically to the constantly-rotating member 9 by the operation of the stop motion in bringing the stitch-forming mechanism to rest, said cam becoming automatically disconnected from its driving member after it has performed its function of holding and cutting the thread and remaining so disconnected until the stop motion again operates to bring the machine to rest. This cam member is indicated at 35 and it is shown as mounted on a stud 36 secured to the frame (see Fig. 5). The cam is provided with two cam portions 37 and 38, one of which actuates the thread-holding finger and the other of which actuates the thread cutter.

The connections by which the thread-holding finger 24 is actuated are as follows. The rock shaft 25 which carries the thread-holding finger 24 has rigid therewith at its upper end an arm 39 from which rises a stud 40 that is received in an open-ended slot 41 formed in the forward end of a thrust member or rod 42. The rear end of this thrust member or rod 42 is pivoted at 43 to an arm 44 that is fast on a rock shaft 45 journalled in suitable bearings 46 carried by the frame. This shaft 45 has fast thereon a follower arm 47 which is engaged by the cam member 37, said arm being held in engagement with the cam by a spring 48. With this arrangement it will be seen that upon each rotation of the cam 37 the arm 47 will be swung to the left thereby rocking the shaft 45 and swinging the arm 44 to the left, which movement will operate through the thrust rod 42 and arm 39 to turn the rock shaft 25 and thus swing the thread-holding arm into the position shown in Fig. 10. When the cam 37 passes out from underneath the arm 47 the thread-gripping arm 120 will be returned to its initial position.

For giving the cutter its movement I have provided the following connections. The thread cutter operates between the work, clamping foot 7 and the clamp plate 32 and

it is formed with an upstanding shank portion 49 which is secured by screws 50 to a sliding head 51 carried by the end of a second thrust member or rod 52. This head 51 is shown as having a guiding slot 53 therein in which is received a guiding stud 54 carried by the head 26. The rear end of the thrust member 52 extends through the upturned end 55 of a rock shaft 56 which is also journaled in the bearing 46, said thrust member 52 having a collar 57 thereon which engages the arm 55 as shown best in Figs. 2 and 4.

The rock shaft 56 has fast thereon a follower arm 58 which is adapted to be engaged by the cam member 38, said arm being acted on by a spring 59 which holds the arm 58 in engagement with the cam. At each rotation of the cam member 35, therefore, the cam portion 38 will actuate the arm 58 moving it to the left Fig. 1 and thereby turning the rock shaft 56 and operating through the arm 55 to move the thrust rod 52 to the left, this movement giving the cutter its thread-cutting movement as will be understood. When the cam 38 passes out from under the arm 58 the spring 59 will return the parts to their normal position.

The cam 35 is normally inactive or idle and my present invention contemplates means controlled by the stop motion for rendering the cam 35 operative.

When the cam 35 is being operated it is driven directly from a rotary driving member 60 which is shown as mounted on the stud 36 and which is in turn geared to the driving member 9. This member 60 is in the form of a gear which has gear teeth on its periphery which mesh with a pinion 61 that is loosely mounted on the shaft 8 but is rigid with the driving member 9. For this purpose the driving member has a sleeve 62 rigid therewith through which the shaft 8 extends and on which the clutch-actuator 10 is slidably mounted. This sleeve is provided with a note 63 in which is received a lug 64 extending from the pinion 61 whereby the pinion is locked to the sleeve and thus is constantly rotating with the driving member 9. Since the pinion 61 is geared to the member 60 said member 60 is also a constantly rotating member.

A clutch is provided for clutching the cam member 35 to the rotating member 60 at the time that the thread holder and cutter are to be actuated. This clutch is herein shown as a clutch pin 64 slidably mounted in the cam member 35 and acted on by a spring 65 tending to throw it into clutching engagement with the rotating member 60, the latter having one or more recesses 66 to receive the pin as shown in Fig. 5. This pin is provided with a head 67 and normally it is held in its retracted position shown in dotted lines Fig. 5 by means of a clutch dog 68 which is in the form of an arm carried by a rock shaft 69

that is also journaled in the bearing 46. The rock shaft 69 is acted on by a spring 70 which tends to hold the clutch dog in the operative position shown in full lines Fig. 1.

When the clutch is disengaged the clutch dog is in its operative position and the head 67 of the clutch pin is engaging the dog and is held in its retracted position shown in dotted lines Fig. 5 and out of clutching engagement with the member 60. When, however, the clutch dog is swung backwardly so as to withdraw it from engagement with the head 67 of the clutch pin then the spring 65 will throw the clutch pin forwardly into clutching engagement with the constantly-rotating member 60 thus coupling the cam to said member. This operation of throwing the clutch into engagement is derived from the action of the stop motion so that the operation of bringing the stitch-forming mechanism to rest will result in clutching the cam 35 to the rotating member 60.

The block 21 of the stop motion is provided with an upstanding finger 71 which has engagement with an arm 72 rigid with the rock shaft 69. When the stop motion operates to bring the stitch-forming mechanism to rest the action of the stop cam 19 on the stop dog 20 will not only force the stop dog 20 downwardly in Fig. 3 against the action of the spring 22 but will also give the block 21 a slight rocking movement toward the right Fig. 3 thus momentarily swinging the finger 71 into the dotted line position. This finger 71 has a return spring 73 connected thereto so that it will immediately be returned to its normal position. The stopping of the stitch-forming mechanism, however, will result in a quick momentary movement of the finger 71 into the dotted line position Fig. 3. During this movement the finger 71 acts on the arm 72 to rock the shaft 69 and thereby raise the clutch dog 68 out of engagement with the head 67 of the clutch pin. This will allow the clutch pin to clutch the cam to the member 60 so that said cam will be rotated by the member 60.

Since the movement of the finger 71 is a momentary movement only the rock shaft 69 will immediately return to its normal position through the influence of the spring 70 so that as the cam member 35 completes its first rotation the head 67 of the clutch pin will engage the inclined face 75 of the clutch dog and will thus be withdrawn from clutching engagement with the member 60. This clutch, therefore, by which the cam 35 is operated, is a one-revolution clutch. It is thrown into clutching engagement by means controlled by the stop motion and it is automatically thrown out of clutching engagement upon the completion of one revolution.

The means above described are for holding and trimming the thread at the end of the sewing operation, the thread being cut be-

tween the thread holder and the work. The thread holder continues its hold on the thread until the next sewing operation has begun thereby to trim the held end of the thread. 5 This means for trimming at the beginning of the sewing operation is illustrated in Fig. 4.

The cam shaft 93 has thereon a cam member 76 which makes one rotation during each sewing operation. This cam member is provided with a cam projection 77 which cooperates with an elbow lever 78 pivoted to the frame at 79. When the sewing machine is started in operation the rotation of the member 76 will cause the cam projection 77 to engage the arm 80 at a period of time after the stitching operation has begun thereby giving the elbow lever 78 a swinging movement. The arm 81 of this elbow lever 78 is situated to engage the end of the thrust rod 52 by which the cutter is actuated and, therefore, after any stitching has begun the push rod 52 will be actuated thus operating the cutter 33 to cut the thread between the holding means and the work, thus trimming the 25 thread close to the work. This movement of the push rod 52 is permitted without being interfered with by the arm 55 by reason of the fact that the push rod extends freely through the upper end of said arm. Said 30 push rod, therefore, is adapted to be actuated either by the arm 55 or by the lever 78. The arm 55 operates the push rod 52 at the end of the seam and the lever 78 operates it at the beginning of the seam.

35 In the construction herein shown the work clamps are raised manually by means of a lever 89 pivoted to the arm at 88 and having a link 87 connected thereto at one end which leads to a treadle, the other end of the lever carrying a lifting member 86 adapted to engage the arms 27 when the treadle is depressed thereby to raise the clamps.

While I have illustrated herein a selected embodiment of the invention I do not wish 45 to be limited to the constructional features shown.

I claim:

1. In a sewing machine, the combination 50 with stitch-forming mechanism, of means for operating said stitch-forming mechanism, a stop motion device to bring the stitch-forming mechanism to rest, which stop motion includes a stop cam and a yieldingly mounted stop dog which has a yielding movement when engaged by the stop cam to bring the machine to rest, a thread trimmer, means set in operation by the yielding motion of the stop dog to actuate the thread trimmer after the stitch-forming mechanism has come to rest, and other means to actuate said thread trimmer after the stitch-forming mechanism has started.

2. In a sewing machine, the combination 55 with stitch-forming mechanism, of operating means therefor, a stop motion device to bring the stitch-forming mechanism to rest, which stop motion includes a stop cam and a yieldingly mounted stop dog which has a yielding movement when engaged by the stop cam to bring the machine to rest, a thread trimmer, a thread holder, means set in operation by the yielding motion of the stop dog to cause action of the thread trimmer after the stitch-forming mechanism has come to rest, and means for operating said thread trimmer at the beginning of a sewing operation by means that actuates the stitch-forming mechanism.

3. In a sewing machine, the combination 60 with stitch-forming mechanism, of a stop motion device to bring the stitch-forming mechanism to rest, which stop motion includes a stop cam and a yieldingly mounted stop dog which has a yielding movement when engaged by the stop cam to bring the machine to rest, a thread trimmer, a thread holder, means set in operation by the yielding motion of the stop dog to cause action of the thread trimmer after the stitch-forming mechanism has come to rest, and means for operating said thread trimmer at the beginning of a sewing operation by means that actuates the stitch-forming mechanism.

4. In a sewing machine, the combination 65 with stitch-forming mechanism, of a stop motion device to bring the stitch-forming mechanism to rest, which stop motion includes a stop cam and a yieldingly mounted stop dog which has a yielding movement when engaged by the stop cam to bring the machine to rest, a thread trimmer, a thread holder, means set in operation by the yielding motion of the stop dog to cause action of both the thread trimmer and the thread holder after the stitch-forming mechanism has come to rest, and means to actuate said thread trimmer at 70 the beginning of each sewing operation.

5. In a sewing machine, the combination 75 with stitch-forming mechanism, of a stop motion device to bring the stitch-forming mechanism to rest, which stop motion includes a stop cam and a yieldingly mounted stop dog which has a yielding movement when engaged by the stop cam to bring the machine to rest, a thread trimmer, a thread holder, means set in operation by the yielding motion of the stop dog to cause actuation of both the thread trimmer and the thread holder after the stitch-forming mechanism has come to rest, and means to actuate said thread trimmer only at the beginning of the sewing operation.

6. In a sewing machine, the combination 80 with stitch-forming mechanism, of operating means therefor, a stop motion device to bring the stitch-forming mechanism to rest, which stop motion includes a stop cam and a yieldingly mounted stop dog which has a yielding movement when engaged by the stop cam to bring the machine to rest, a thread trimmer, a thread holder, means set in operation by the yielding motion of the stop dog to cause actuation of both the thread trimmer and said thread holder, and means to actuate the thread trimmer at the beginning of the seam by the operating means for the stitch-forming mechanism.

7. In a sewing machine, the combination 85 with stitch-forming mechanism, of operating means therefor, a stop motion device to bring the stitch-forming mechanism to rest, which stop motion includes a stop cam and a yieldingly mounted stop dog which has a yielding movement when engaged by the stop cam to bring the machine to rest, a thread trimmer, a thread holder, means set in operation by 90

the yielding movement of the stop dog to cause actuation of the thread trimmer and the thread holder after the stitch-forming mechanism has come to rest, and means to actuate said thread trimmer at the beginning of the seam by the operating means for the stitch-forming mechanism.

7. In a sewing machine, the combination with stitch-forming mechanism including a needle operating from above the work, of a constantly-rotating driving member, a clutch for driving the stitch-forming mechanism from the driving member, a stop motion device to disengage the clutch and bring the stitch-forming mechanism to rest at the end of a seam, and means to trim the needle thread above the work, said means being controlled by the stop motion and deriving its thread-cutting movement from the driving member.

8. In a sewing machine, the combination with stitch-forming mechanism, including a needle operating from above the work, of a constantly-rotating driving member, a clutch for driving the stitch-forming mechanism from the driving member, a stop motion device to disengage the clutch and bring the stitch-forming mechanism to rest at the end of a seam, and means controlled by the stop motion but deriving its thread-cutting movement from the driving member to trim the needle thread above the work after the stitch-forming mechanism has come to rest.

9. In a sewing machine, the combination with stitch-forming mechanism, of a constantly-rotating driving member, a clutch for driving the stitch-forming mechanism from the driving member, a stop motion device to disengage the clutch and bring the stitch-forming mechanism to rest at the end of a seam, means to grip and hold the thread and means controlled by the stop motion but deriving its thread-cutting movement from the driving member to cut the thread between the holding means and the work.

10. In a sewing machine, the combination with stitching-forming mechanism, of a constantly-rotating driving member, a clutch for driving the stitch-forming mechanism from the driving member, a stop motion device to disengage the clutch and bring the stitch-forming mechanism to rest at the end of a seam, means controlled by the stop motion but actuated by the driving member after the stitch-forming mechanism has come to rest to seize and hold the thread and then to cut the thread between the holding means and the work.

11. In a sewing machine, the combination with stitch-forming mechanism including a needle penetrating the work from above, of operating means therefor, a stop motion device to bring the stitch-forming mechanism to rest, which stop motion includes a stop cam and a yieldingly mounted stop dog which has a yielding movement when engaged by the

stop cam to bring the machine to rest, means to seize and hold the needle thread above the work, a thread trimmer to cut the thread between the holding means and the work, and means set in operation by the yielding movement of the stop dog to cause actuation of the thread trimmer and thread holder after the stitch-forming mechanism has come to rest, and other means to actuate the thread trimmer after the next stitching operation has started.

12. In a sewing machine, the combination with stitching-forming mechanism, a constantly-rotating driving member, a clutch for driving said stitch-forming mechanism from the driving member, a stop motion device to disengage the clutch and bring the stitch-forming mechanism to rest at the end of the seam, means to seize and hold the thread, a thread trimmer for cutting the thread between the holding means and the work, and means controlled by the stop motion but actuated by said driving member for actuating the thread holder and the thread trimmer at the end of the seam, and means to actuate the thread trimmer at the beginning of the seam.

13. In a sewing machine, the combination with stitch-forming mechanism, of a stop motion device for bringing the stitch-forming mechanism to rest at the end of the sewing operation, a constantly-rotating member a thread trimmer, and means controlled by the stop motion but actuated by the constantly-rotating member to operate the thread trimmer to cut the thread after the stitch-forming mechanism has been brought to rest and other means to operate said thread trimmer at the beginning of the sewing operation.

14. In a sewing machine, the combination with stitch-forming mechanism, of a stop motion device for bringing the stitch-forming mechanism to rest at the end of the sewing operation, a constantly-rotating member, a thread trimmer, means controlled by the stop motion but actuated by the constantly-rotating member to seize and hold the thread after the stitch-forming mechanism stops and then to actuate the thread trimmer to cut the thread at the end of the sewing operation, and other means to actuate the trimmer at the beginning of the sewing operation.

15. In a sewing machine, the combination with stitch-forming mechanism, of operating means therefor, a stop motion device for bringing the stitch-forming mechanism to rest at the end of a sewing operation, a constantly-rotating member, a thread holder, a thread cutter, means controlled by the stop motion but actuated by the constantly-rotating member to actuate the thread holder and the thread cutter after the stitch-forming mechanism has come to rest, and other means to actuate the cutter at the beginning of the sewing operation.

16. In a sewing machine, the combination

with stitch-forming mechanism, of operating means therefor, a stop motion device for bringing the stitch-forming mechanism to rest at the end of a sewing operation, a constantly-rotating member, a thread holder, and a thread cutter, means controlled by the stop motion but actuated by the constantly-rotating member to actuate the thread holder and the thread cutter after the stitch-forming mechanism has come to rest, and means to actuate the thread cutter at the beginning of the sewing operation.

17. In a sewing machine, the combination with stitch-forming mechanism, of operating means therefor, a constantly-rotating member, a thread trimmer, a cam for actuating the thread trimmer, normally disconnected from the constantly-rotating member, a stop motion for bringing the stitch-forming mechanism to rest, which stop motion includes a stop cam and a yieldingly mounted stop dog which has a yielding movement when engaged by the stop cam to bring the machine to rest and means actuated by the yielding movement of the stop dog to connect said cam to the constantly-rotating member whereby the trimmer is operated.

18. In a sewing machine, the combination with stitch-forming mechanism, of operating means therefor, a stop motion for bringing the stitch-forming mechanism to rest, which stop motion includes a stop cam and a yieldingly mounted stop dog which has a yielding movement when engaged by the stop cam to bring the machine to rest, a thread trimmer, a thread holder, a constantly-rotating member, a cam device for actuating the thread holder and giving the thread trimmer its thread cutting movement, which cam is inoperative during the sewing operation, a one-revolution clutch for connecting the cam to the constantly-rotating member, and means set in operation by the yielding motion of the stop dog to throw said clutch into engagement.

19. In a sewing machine, the combination with stitch-forming mechanism, of means for operating said stitch-forming mechanism, a stop motion device to bring the stitch-forming mechanism to rest, which stop motion device includes a stop cam and a yieldingly mounted stop dog which has a yielding movement when engaged by the stop cam to bring the machine to rest, a thread trimmer, and means set in operation by the yielding motion of the stop dog to actuate the thread trimmer after the stitch-forming mechanism has come to rest.

20. In a sewing machine, the combination with stitch-forming mechanism, of means for operating said stitch-forming mechanism, a stop motion device to bring the stitch-forming mechanism to rest, which stop motion device includes a stop cam and a yieldingly mounted stop dog which has a yielding movement

when engaged by the stop cam to bring the machine to rest, a thread trimmer, and means set in operation by the yielding motion of the stop dog to grip the thread and to actuate the thread trimmer to cut the thread after the 70 stitch-forming mechanism has come to rest.

In testimony whereof, I have signed my name to this specification.

JOHN KIEWICZ
